CONTAINER CLOSURE

Jack W. Soffer, St. Louis, Mo.

Application June 29, 1950, Serial No. 10,830

Term of patent 14 years

(Cl. D58—26)

To all whom it may concern:

Be it known that I, Jack W. Soffer, a citizen of the United States, residing at the city of St. Louis, State of Missouri, have invented a new, original, and ornamental Design for a Container Closure, of which the following is a specification, reference being made to the accompanying drawing, forming a part thereof, in which

Figure 1 is a top view of a container closure embodying my new design;

Figure 2 is an end view thereof;

Figure 3 is a side elevational view thereof;

Figure 4 is a side section thereof taken along line 4—4 of Figure 1; and

Figure 5 is a bottom view thereof.

I claim:

The ornamental design for a container closure, substantially as shown.

JACK W. SOFFER.
